DESIGN FOR A SET OF NUMERALS OR SIMILAR ARTICLES

Herman Kursh and Sam M. Harris,
Cleveland, Ohio

Application April 24, 1943, Serial No. 110,032

Term of patent 14 years

(Cl. D64—12)

To all whom it may concern:

Be it known that we, Herman Kursh, a citizen of the United States, residing at 3357 E. 146th Street, and Sam M. Harris, a citizen of the United States, residing at 12912 Woodland Avenue, both of Cleveland, in the county of Cuyahoga and State of Ohio, have invented a new, original, and ornamental Design for a Set of Numerals or Similar Articles, of which the following is a specification, reference being had to the accompanying drawing, forming a part thereof.

Fig. 1 is a plan view of a set of numerals embodying our new design; and

Fig. 2 is an edge view of one of the numerals thereof.

We claim:

The ornamental design for a set of numerals or similar articles, as shown.

HERMAN KURSH.
SAM M. HARRIS.
